PROCESS OF MANUFACTURING GELATIN
BLASTING EXPLOSIVEStanley Fordham, Saltcoats, Scotland, assignor
to Imperial Chemical Industries Limited, a cor-
poration of Great BritainNo Drawing. Application February 3, 1947, Se-
rial No. 726,227. In Great Britain March 14,
1946

4 Claims. (Cl. 52—22)

1

The present invention relates to the manufacture of improved or modified gelatine blasting explosives.

By the term "gelatine blasting explosives" I mean blasting explosives of coherent consistency containing a sufficient proportion of a jelly comprising nitrocellulose in solution in one or more liquid explosive nitric esters to render the explosive capable of being cartridgeed by extrusion. The most powerful of the gelatine blasting explosive compositions, known as blasting gelatine, consists of practically undiluted nitroglycerine jelly, and there is also available a series of less powerful explosives which comprise vegetable tissue materials of more or less porous structure and of oxidisable character and oxidising salts, for instance woodmeal and inorganic nitrates distributed through a liquid explosive nitric ester-nitrocellulose jelly.

As is well known wet nitrocellulose is frequently used for gelatine blasting explosives and this may contain 30% or more water. When nitrocellulose is added in this form to liquid nitric esters there is a tendency to form pips.

The object of the present invention is to provide a process for producing more homogeneous gelatine blasting explosives having wet nitrocellulose incorporated therein than have been produced heretofore.

I have now found that the inclusion of a wetting agent amongst the ingredients of the gelatine blasting explosive that contains wet nitrocellulose results in a marked diminution in the occurrence of pips in the final product.

According to the present invention, therefore, a gelatine blasting explosive containing wet nitrocellulose has a wetting agent distributed through said explosive.

The process according to the invention for the production of a gelatine blasting explosive comprises mixing wet nitrocellulose, soluble in nitroglycerine, and one or more liquid explosive nitric esters in the presence of a wetting agent.

Almost any anionic or non-ionic agent may be used which is preferably added to the water of the nitrocellulose if water-soluble or to the liquid explosive nitric ester if water-insoluble. For instance, non-ionic agents as for example polyglyceryl ricinoleate may be dissolved in the liquid nitric ester in the preparation of gelatine blasting explosives. On the other hand, it is necessary for an anionic wetting agent as for example sodium dibenzyl sulphinate or the sodium salt of isopropyl naphthalene sulphonic acid to be in solution in the water associated

5 with the nitrocellulose prior to mixing the said nitrocellulose with the liquid explosive nitric ester. The best results have so far been obtained by having in solution up to 5% of a sulphonate wetting agent in the water associated with the nitrocellulose.

10 In a gelatine blasting explosive according to the invention the quantity of wetting agent is preferably between 0.2 and 2% calculated on the dry nitrocellulose present.

15 The term "wetting agent" is meant to include anionic or non-ionic organic wetting dispersing and emulsifying agents having the property of assisting the wetting of nitrocellulose by water.

20 It is desirable that the initial mixing of the nitrocellulose and the one or more liquid explosive nitric esters and wetting agents should take place in the absence of any gelatinisation accelerator.

25 The invention is illustrated by the following examples in which the parts are parts by weight. By the term "blasting soluble nitrocellulose" used in the following examples is meant, the product obtained by the nitration of purified cotton cops by the pot process to a nitrogen content of 11.95 to 12.15% and which is at least 95% soluble in a mixture of ether and alcohol (66 O. P.) in the proportion by volume of 2:1 and has a viscosity of 100 to 300 c. g. s. units in 100 ml. acetone 95% at 30 20° C.

Example I

Blasting soluble nitrocellulose in the course of its manufacture is given a last wash with a 1% aqueous solution of sodium isopropyl naphthalene sulphonate. This is then pressed to a moisture content of 28%. The content of wetting agent is 0.4% calculated on the dry nitrocellulose. After breaking down the lumps the wet nitrocellulose is mixed into a smooth gel with nitroglycerine without such precautions as for example blending with inert material. This smooth gel is suitable for use as a base in the manufacture of blasting explosives.

Example II

50 Blasting soluble nitrocellulose is given a last wash with a 4% aqueous solution of sodium dibenzyl sulphinate. This is then centrifuged or pressed to a moisture content of 33%, and the lumps broken down. The content of wetting agent is about 2% calculated on the dry nitrocellulose. The resultant nitrocotton is used in the 55 manufacture of gelatine blasting explosives, as

for example Polar Ammon Gelignite of the following composition:

	Parts
Low freezing nitroglycerine	34.0
Centrifuged wet nitrocellulose (2% sodium dibenzyl sulphamate calculated on the dry nitrocellulose)	1.5
Liquid nitrobody mixture	1.8
Wood meal	4.0
Oat husk meal	3.6
Ammonium nitrate	36.1
Sodium nitrate	19.0

The low-freezing nitroglycerine contains 4 parts nitroglycerine with 1 part ethylene glycol dinitrate.

The nitrocellulose, woodmeal and oat husk meal are placed in a rubber lined box, and the nitroglycerine added. The whole are given a preliminary mixing by hand, and the liquid nitrobody mixture then added. The jelly thus obtained is allowed to stand for at least one hour, and then transferred to the bowl of a McRoberts mixer. The stirrers are rotated, the ammonium nitrate and sodium nitrate added, and the whole mixed for 35 minutes at 20° C. The resultant explosive may be cartridge by extrusion, and is completely uniform and free from pips.

Example III

The invention may be applied in the manufacture of Polar Ammon Gelignite of the following composition:

	Parts
Nitroglycerine	34.0
Wet blasting soluble nitrocellulose, containing 30% water	1.2
Polyglyceryl ricinoleate	0.5
Wood meal	4.0
Ammonium nitrate	36.3
Sodium nitrate	24.0

The wetting agent, polyglyceryl ricinoleate, is dissolved in the nitroglycerine, which is then added to the wet nitrocellulose and wood meal in a rubber lined box. After a preliminary mixing by hand, the resultant jelly is allowed to stand for one hour. The jelly is then mixed with the ammonium nitrate and sodium nitrate and extruded, as in Example II. The resultant explosive is again uniform and free from pips.

I claim:

1. A process for the production of gelatine blasting explosives which comprises mixing one part by weight of water wet nitrocellulose, 0.2 to 2% by weight of a neutral organic wetting agent

having the property of assisting the wetting of nitrocellulose by water and selected from the group consisting of sodium isopropyl naphthalene sulphonate, sodium dibenzyl sulphamate, and polyglyceryl ricinoleate, and at least 9 parts by weight of at least one liquid nitric ester, the weight of said neutral organic wetting agent being calculated on the basis of the weight of the dry nitrocellulose present.

2. A process for the production of gelatine blasting explosives which comprises mixing sodium isopropyl naphthalene sulphonate in a proportion of 0.2 to 2% by weight with one part by weight of water wet nitrocellulose and thereafter adding at least 9 parts by weight of at least one liquid nitric ester, the weight of sodium isopropyl naphthalene sulphonate being calculated on the basis of the weight of the dry nitrocellulose present.

3. A process for the production of gelatine blasting explosives which comprises mixing sodium dibenzyl sulphamate in a proportion of 0.2 to 2% by weight with one part by weight of water wet nitrocellulose and thereafter adding at least 9 parts by weight of at least one liquid nitric ester, the weight of sodium dibenzyl sulphamate being calculated on the basis of the weight of the dry nitrocellulose present.

4. A process for the production of gelatine

blasting explosives which comprises mixing polyglyceryl ricinoleate in a proportion of 0.2 to 2% by weight with at least 9 parts by weight of at least one liquid nitric ester, and thereafter adding one part by weight of water wet nitrocellulose, the weight of the polyglyceryl ricinoleate being calculated on the basis of the weight of dry nitrocellulose present.

STANLEY FORDHAM.
